UNITED STATES PATENT OFFICE.

LEVI GOUDRICH, OF SAN JOSE, CALIFORNIA.

IMPROVEMENT IN BUILDING BRICK WALLS FOR HOUSES, &c.

Specification forming part of Letters Patent No. 44,418, dated September 27, 1864.

To all whom it may concern:

Be it known that I, LEVI GOUDRICH, of San José, in the county of Santa Clara and State of California, have invented a new and useful Improvement in Hollow Brick walls for Buildings and other purposes; and I do hereby declare that the following is a full, clear, and exact description thereof, which will enable others skilled in the art to make and use the same, reference being had to the accompanying drawings, making a part of this specification, in which—

Figure 1 represents a transverse vertical section of a brick wall, laid or put up according to my invention; Fig. 2, a horizontal section of the same, taken in the line $x x$, Fig. 1. Figs. 3, 4, 5, and 6 are horizontal sections of modifications of the same; Fig. 7, a transverse vertical section of a modification of the same; Fig. 8, a horizontal section of Fig. 7, taken in the line $y y$.

Similar letters of reference indicate like parts.

Specification of Goodrich's improved hollow brick walls, showing the mode of constructing them, also their superiority for buildings and other purposes, over the common or solid brick walls, in cheapness, strength, and comfort.

The following is a description of their construction for an ordinary building of two or three stories in height with walls twelve inches thick, and this description will answer in many respects for most walls: The foundation-walls A, if of the ordinary height, I would lay up in the usual style solid to the height of the under side of the first tier of floor-beams B, tying them in the usual way, or with wood, as hereinafter described, for the hollow walls. From this last-named level (the under side of first tier of floor-beams) I build two four-inch (half-brick) walls, C C, separated by an air space or chamber, D, of four inches along the center of the walls, all the bricks being laid as stretchers with a full and perfect bond with each other up to the next tier of floor-beams, E, introducing in the mortar-joints at every fourth, fifth, or sixth course, or as often as may be thought best, as ties strips of wood or pieces of hoop iron, F, to tie the four-inch walls together to prevent them separating or collapsing, and otherwise strengthening the walls. These strips I

lay diagonally across from one four-inch wall to the other—say at an angle of forty-five degrees, or at a greater or less angle with the face of the wall, as one may think best. (See Fig. 2.) These strips of wood or ties I introduce in various ways. They may be placed in every joint, or in every third, fourth, or fifth joint, or as often as may be thought best, and along on the wall about a foot or ten inches apart or nearer, measuring parallel with and along the wall and at an angle with the face of the wall of about forty-five degrees or at a greater or less angle, laid upon the naked brick, their ends extending to near the inner and outer faces of the wall, and buried in and overlaid by the following joint of mortar and layer of bricks. The next course of ties or braces are laid at the same angle to the face of the wall, but in the opposite direction from the preceding ties, and this rule I observe throughout the wall, the ties constantly alternating, appearing, when looking down the hollow space along the center of the wall, like lattice or herring-bone bridging between floor-beams, and giving the same character of support to the walls as such bridging does to floor-beams, in addition to tying the walls in every other direction.

Opposite and at the ends of every set of floor-beams above the foundation beams, and entirely around the building, I build the walls solid the depth of the beams, as shown at a, Figs. 1 and 7, as no dampness can ever penetrate or do harm at this point to any of the apartments, as the wall-plate would prevent all dampness going to the walls below it. This solid brick-work of four or five courses gives every facility for anchoring the floor-beams to the exterior walls, and also distributes more equally the weights of the floors, roof, &c., over both the inside and outside walls, and makes both walls support alike the superstructure.

For walls for carrying very great weight or of great height I adopt the following method: I increase the inner or outer wall to a single brick, (eight-inch wall,) or build three four-inch walls, G, (see Fig. 7,) with two air-chambers, b b, or spaces of any desired width from an inch to four inches or more, and let the laths or ties H run diagonally across the three courses, as shown in Fig. 8, or build two single brick walls (eight-inch walls) with single

air-space in the center, and tie the same, as shown in Fig. 4, or build with internal alternating piers or buttresses *e*, as shown in Figs. 3 and 6. Either of these modes would answer for any place where a solid wall of the same thickness would answer, with all the herein-after-mentioned advantages of a hollow wall and ties and braces. A hollow wall, *I*, with hollow space or chamber, is shown in Figs. 4 and 6, with bricks on edge. This if well laid up and tied at every second or third course, will make as strong or a stronger wall to resist any ordinary strains that small buildings are subject to than the ordinary eight-inch solid wall, thereby saving over one-third of the bricks and one-half the mortar of the ordinary eight-inch solid wall, with other advantages of the wall. Showing the width of bricks to view, of course, with our present ideas of proportion for brick work, would not be as pleasing as when laid the usual way, but when a house is designed to be stuccoed outside this objection of looks would be removed. This mode would be an excellent one for partition-walls. The air-space in this wall for an outside wall it might be advisable to make some larger—say four or five inches wide—giving, of course, so much more base to the wall, and, of course, adding materially to its strength. I also introduce, to give additional strength to the walls where it may be required, internal alternating piers or buttresses *e*, previously alluded to. These piers or buttresses, it will be seen, do not touch but one of the walls. This style of wall will make a very strong building, considering the thickness of the respective walls.

I have another plan of tying hollow walls, which consists of a large continuous wire, *f*, (see Fig. 5,) say about the size of telegraph-wire. This I run zigzag from one wall to the other, lapping on each wall some three inches, and continuing entirely around the building, or from opening to opening. It makes an excellent tie.

I will now mention some of the advantages of this style of hollow brick walls over the ordinary solid walls, especially where the wood or hoop-iron ties or braces are used. The former I should always use, and the latter only where great danger exists from fire, and then even I would alternately in every course use them with the wooden ties, as the wood makes much stiffer work.

I will speak of the ordinary twelve-inch wall; and when I speak of bricks I speak of them as eight by four by two and a half inches. First, a saving from the foundation of one-third the bricks, one-half the mortar, and one-third the labor, saves all plugging of walls and wooden bricks for attaching casings, washboards, and all other trimmings both for the inside and the outside, as the ties may be laid through the walls at convenient points for these purposes, and I find from practice that they answer admirably well for this purpose; saves all furring off of walls and lathing them,

as the plastering may be applied directly to the brick walls without any danger of stains or dampness, and makes much better and more solid work, and is entirely free from all cracks. It makes a much stronger wall every way. On a strain with its length, it will be seen, all the bricks are laid, stretchers, and all of course have a perfect bond with each other. This style also looks much better, as all the bricks being laid stretchers give it the appearance, as far as the bond is concerned, of a pressed brick front. It also makes a stronger wall to resist direct weight—that is, resistance to compression—the same reasoning applying to it that proves a hollow column above a certain height or length and of a certain thickness to be stronger than a solid one. These walls give every facility for ventilation for laying through them gas-pipes, water-pipes, soil-pipes, and all other pipes which may be used about a building. There is much less difficulty in keeping this kind of wall plumb or from swaying while building, and while putting up floor-beams and other timbers, as experience has shown, and the wall as a whole to be much stiffer. In fact there is no difficulty in keeping it plumb and from swaying contingencies, which usually attend building of high and continuous solid walls. This is not alone the effect of the peculiar mode of bracing, which, of course, would and does have this effect; but the fact that the heart of the wall being gone the wall inside dries as fast as outside while going up, thereby allowing all parts of the wall to settle alike and together, and throwing the weight of the wall and superstructure equally upon the whole wall, which is not the case while building the ordinary solid walls, which, while the latter shrinks on both surfaces, and does settle when it can on one surface or the other faster than the heart of the wall, thereby throwing the wall out of plumb, and out of line. This fact all builders acquainted with brick-work are familiar with, and is the main cause of walls swaying out of plumb and out of line while the walls are new and the mortar green. There are other qualities this style of wall possesses that recommend it, especially in a country subject to earthquakes, among which are lightness, its elasticity or yielding nature to a sudden shock. It is a conceded fact that a light wall will resist the shock of an earthquake better than a solid one, as there is not the amount of momentum while in motion as in the heavy wall; and I further believe that walls constructed as I here show them may be shaken until there is no bond between any of the bricks, and the ties or braces alone will hold it together and prevent the wall falling; but the great protection these walls afford against dampness, the great evil of all brick buildings built in the usual way, and in this respect it is perfect, and from fire from without and within, and against heat and cold, the great facility for ventilation in every part of the building, and the very great saving in the expense of building, and the additional

strength of these walls must recommend them above all other modes of building brick walls now in use.

Partially hollow brick walls is no new thing. There are many modes of making them, as shown in London's (English) Encyclopedia of Cottage, Farm, and Villa Architecture, where Dean's and Silverlock's methods are treated of at length, also Downig's method, as shown in his "Country Houses," as well as many other American, English, French, and German methods I might name; but the mode I have here introduced differs from them all. Theirs are tied with brick. This mode of alternating diagonal lattice tying, or bridging with wood, iron, and other materials, as well as the alternating interior buttresses or piers, in their various shapes, as shown by me, as well as the zigzag wire tying, I believe to be entirely new.

While I admit all the advantages claimed for the ordinary partially hollow brick walls, all of which advantages my mode possesses, they are all quite imperfect. There are none of

them less than one-fourth, and the most of them are from one-third to one-half, their superficial area solid, possessing, of course, to that extent all the objections of a solid brick wall, lacking the many and great advantages I claim for the lattice bracing and tying.

I claim as new and desire to secure by Letters Patent—

1. The employment or use in hollow brick walls of angular diagonal lattice, or herring-bone bridging, or, in other words, bracing and tying with wood, iron, stone, or other material laid in the mortar-joints while the walls are in course of erection, substantially as and for the purpose herein set forth.

2. The internal brick piers or buttresses *e*, when used in connection with hollow walls and ties or braces, substantially as and for the purpose specified.

LEVI GOODRICH.
